UNITED STATES. PATENT OFFICE.

JAMES WHALEN, OF OMAHA, NEBRASKA.

FLUID-POLE ELECTRIC SWITCH.

Application filed October 15, 1926. Serial No. 141,752.

My invention relates to electric switches of the general class in which one or more poles of the switch consist of fluid metal such as mercury. It is the object of my invention to provide for switches of this class a pole-forming composition having much greater electrical conductivity than mercury alone, and of sufficient fluidity at ordinary temperatures to assume by gravity the formation of the lower-most portion of the container in which the composition is held. A further object of my invention is to provide means for limiting oxidation of the fluid metal composition without hermetically sealing the same to exclude air therefrom. A further object of my invention is to provide an electric switch in which the moving parts are so constructed and arranged as to be operable with a very small mechanical force, although the poles and other parts are of such conductivity as to transmit heavy electric current without heating while the switch is closed and without objectionable arcing as the switch is opened. A further object of my invention is to provide a switch mechanism having the above characteristics and adaptable to produce a multiple break of the electric circuit when in open position, whereby the switch may be employed in high-voltage circuits.

In the accompanying drawings Fig. 1 is a longitudinal section of a switch embodying my invention, the parts being shown in circuit-opening position, Fig. 2 is a transverse section on the line 2—2 of Fig. 1, Fig. 3 is a view similar to Fig. 2 but showing the parts in circuit-closing position, Fig. 4 is a detail section on the line 4—4 of Fig. 1, and Fig. 5 is a detail longitudinal section through the vent-valve, the section being on the line 5—5 of Fig. 2.

In carrying out my invention according to the illustrated embodiment thereof, I provide a fixed frame comprising the metal end-members or brackets 10 and 11, secured to a base 12 of insulating material. On the lower portions of said brackets are mounted the binding-posts 13 and 14 to which are connected the terminals of the circuit to be controlled by the switch. In the upper portions of the brackets are axially alined openings in which are revolvably mounted the trunnions or pivot-shafts 15 and 16 of an oscillatable drum which is the movable element of the switch. Said drum comprises the metal end-caps 17 and 18, which may be formed integrally with the pivot-shafts 15 and 16 respectively, two or more cylinder-sections 19 of insulating material such as glass, and one or more T-rings 20 disposed between the adjoining ends of the cylinder-sections 19, the flanges of the T-ring 60 and of the end-caps fitting over the sides of the cylinder-sections as shown, and the parts being secured to each other by suitable cement 21. In the drawing the thickness of the cement in the joints is exaggerated, and it will be understood that the actual thickness thereof is so small as to be imperceptible without such exaggeration. Each of the cylinder-sections has at the central part thereof a transverse partition 22, formed integrally therewith, and the partition at one side of the cylinder has a substantially semi-circular opening therein, the edges of the partition at said opening being preferably rounded or beveled, and the openings of the several sections being axially alined with each other, as shown in Fig. 1. On the pivot-shafts 15 and 16, adjoining the end-caps, are disposed the collars 23, each of which has at one side thereof a small set-screw 24 extending in to an annular groove 25 in the bore thereof, and also has at the side opposite the set-screw an opening extending from said groove to the outside of the collar. Flexible conductors 26, such as are formed by fine wires braided together, are connected with the binding-posts 13 and 14, and extended therefrom through the side-openings of the collars into the annular grooves 25, thence being extended around in said grooves and beneath the ends of the set-screws 24 as shown in Fig. 4, so that when the set-screws are tightened down they serve to firmly connect both the flexible conductors and the collars to the respective pivot-shafts.

The end-cap 17 is provided at one side with a threaded opening in which is screwed a valve-tube 27, the latter projecting into the drum and having at its inner end a seat for the ball-valve 28 which is normally held against the seat by a spring 29, and said spring being retained in the tube by a perforate plug 30 screwed into the outer end of the tube, as shown in Fig. 5.

Within the drum formed by the members 17, 18, 19 and 20, is disposed a body 31 of fluid metal, which is preferably of the composition hereinafter set forth, although if the switch is not to be used for heavy current the metal may be mercury only. A portion of the space within the drum above the fluid metal is preferably filled with a body 32 of insulating liquid, such as heavy hydrocarbon oil, and the

- remaining space at the upper portion of the drum is left empty, or so as to be filled only with air or by vapors from the oil. When the drum is turned to a position such as shown 5 in Fig. 3, at which the openings through the partitions 22 of the cylinder-sections are at the lower portion of the drum, the body 31 of fluid metal forms a conductive connection between the end-caps 17 and 18, and thus closes 10 the circuit of which the terminals are connected with said end-caps through the collars 23, the flexible conductors 26, and the binding-posts 13 and 14. By rotation of the drum from the circuit-closing position approxi- 15 mately a half-revolution, the partitions 22 are caused to cut through the body of fluid metal, thus dividing the same into a plurality of pools which are separated from each other by the partitions as shown in Fig. 1, and the 20 circuit is thus opened at a plurality of points, the number being according to the number of partitioned cylinder-units used in forming the drum. In order that the breaking of the 25 circuit at the several points may be simultaneous, and arcing in high-voltage circuits thus suppressed, it is necessary that the openings through the partitions be aligned with each other, and that the axis of the drum be horizontal, so that the liquid level is parallel 30 therewith.
- The fluid metal composition, which is preferably employed in the switch, is a mixture of mercury and a metal of high electrical conductivity, such as copper or silver, said metal 35 being in small particles which are mixed with the mercury, being immersed therein and superficially amalgamated, but not wholly dissolved therein. The resulting mass is not homogeneous, but is a slushy mixture of ac- 40 tual liquid with solid particles floating therein, the liquid portion of the mixture being mercury having a small proportion of the other metal dissolved therein. The ratio of the liquid to the solid metal in the compo- 45 sition is such that the mass as a whole is fluid or freely mobile, and capable of flowing by gravity into the lowermost portion of the container in which it is held, while main- 50 taining a substantially level or horizontal upper surface. A suitable composition consists of one part, by weight, of copper, with three parts of mercury, the copper being finely di- 55 vided into particles or granules such as are produced by filing or grinding. This compo- 60 sition has an electrical conductivity approxi- mately four times that of mercury alone, and has sufficient fluidity to operate satisfactorily in the described switch mechanism. A 65 larger proportion of the solid metal may be employed, with a corresponding increase in conductivity, by the use of the solid metal in small uniform spherical particles. To insure the thorough amalgamation superficially of the solid metal particles, the latter may be washed with a suitable acid, capable of re-

moving oxide from the metal, prior to mixing with the mercury. After the metals have been mixed for a sufficient time for the solid particles to become thoroughly coated with amalgam, the mixture is thoroughly washed to remove all traces of acid, and is then carefully dried before being used in the switch. 70

The switch-drum may be rotated or oscillated by any suitable actuating means connected with the pivot-shaft 15, and it will be 75 apparent that a very small mechanical force will be sufficient to operate the switch, which is thus adapted for many special purposes, such as the control by thermostat of electrical apparatus employing heavy current, without 80 the use of relays or intermediate switches. The actuating means is preferably so arranged that during the operation the valvete 27 will be constantly above the axis of the drum, so as not to pass below the level 85 of the fluid metal.

During the circuit-opening operations of the switch arcing at the fluid metal poles is suppressed by the insulating liquid 32, and said liquid also serves at all time to limit oxidation of the fluid metal. During extended use of the switch some oxidation of the fluid metal will occur, because of the fact that the drum is not hermetically sealed to entirely exclude air therefrom, but as the oxide is produced in a finely divided or pulverulent form and becomes mixed with the oil and suspended therein without appreciably reducing its insulating qualities, the oxidation does not interfere with the operation of the switch except after long continued use thereof, and the switch may then be restored to its original condition by supplying fresh oil, after first removing the oxide-contaminated oil from the drum. 95

A vent or safety outlet from the drum, to relieve pressure therein should the same be abnormally heated, is formed by the valved passage through the tube 27, and the valve 28 serves to exclude air from the drum, except 100 in very minute quantities such as may be due to leakage. As before mentioned, the insulating liquid 32 may be a rather heavy hydrocarbon oil, and when oil of this kind is used it is preferable when first preparing the switch 105 for use to add to the heavy oil in the drum a drop or two of a light volatile oil such as naptha, then placing the drum so that the tube 27 is above the liquid level, and then heating the same sufficiently to vaporize the volatile oil and thereby expel most of the air from the drum, leaving the space above the liquid filled only with the oil vapor. I have found that very satisfactory results are also attained by the use in place of mineral or hydrocarbon oil, of a non-drying fixed oil such as olive oil, which appears to prevent oxidation of the fluid metal in the switch for a longer time than the mineral oils which I have tested, possibly 110 because the small amount of oxygen which 115

obtains access to the drum combines chemically with the oil itself instead of becoming merely dissolved therein and thus available for combination with the metal.

5 It will be obvious that any desired number of the partitioned cylinder-sections may be employed in forming the drum, and that in operation an additional break of the circuit will be effected for each added partition or 10 divider, the switch being thus adapted for use in circuits of any voltage.

Now, having described my invention, what I claim and desire to secure by Letters Patent is:

15 1. In an electric switch, a pole-forming composition consisting of a large number of separate small bodies of solid metal of high electrical conductivity, in combination with liquid metal connecting the bodies of solid 20 metal interstitially and sufficient in quantity to make the mass as a whole substantially fluid.

2. In an electric switch, a pole-forming composition consisting of mercury, and a large number of separate small bodies of solid metal immersed in the mercury, the mass as a whole being substantially fluid. 25

3. In an electric switch, a pole-forming composition consisting of mercury, and a large number of separate small bodies of solid metal immersed in and superficially amalgamated with the mercury, the mass as a whole being a slushy fluid. 30

4. In an electric switch, a pole-forming composition consisting of a large number of separate small bodies of solid metal of high electrical conductivity, in combination with a quantity of liquid metal connecting the solid bodies interstitially and forming a slushy fluid mass, the liquid metal being a fluid amalgam of mercury with the metal of which the solid bodies are formed. 35 40
